UNITED STATES PATENT OFFICE

ZOLTÁN THOMKA, OF BUDAPEST, HUNGARY

DEVICE FOR PREVENTING CREEP IN RAILWAY RAILS

Application filed April 26, 1928, Serial No. 272,939, and in Hungary May 11, 1927.

It is generally known that the rails situated in the track on the superstructure of railways, have a considerable tendency to creep under the action of the trains, especially when the brakes are applied. This creeping of the rails sets up very dangerous distortions of the superstructure, the displaced rail joints causing unpleasant lateral swaying of the vehicles. Railway companies have endeavored to prevent rail creep by means of numerous devices, on account of the dangers involved. The devices hitherto employed share the common defect of needing continuous inspection and maintenance, and of being expensive, so that, in consequence, can only be used in limited number on a section of track, the result being that the measures of preventing creep are imperfect.

The present invention completely obviates the aforesaid defects of the existing devices for preventing rail creep, since the device constituting the invention requires no upkeep and, owing to its low cost, can be used on all sleepers; apart from the fact that it is stronger than the existing and many times more expensive devices.

Two embodiments of the invention are illustrated in the accompanying drawing.

Figures 1 and 2 show the simple device for preventing rail creep, said device consisting of the flat piece of iron strip *b*, which embraces the foot of the rail *a* as shown in the drawing.

Figure 1 shows a cross section of the rail *a*, the simple device *b* for preventing creep, disposed thereon, and an end view of the tie plate *c* disposed underneath the rail.

Figure 2 shows the rail *a*, with the simple device *b* for preventing creep, in end section, said device bearing against the tie plate *c*.

The iron strip *b* bent round the foot of the rail is applied to the rail foot while red hot and is hammered on to same, so that, in consequence of the contraction occurring on cooling, the strip grips the rail foot with considerable force.

The strips attached to the rail foot are distributed at such intervals along the rail that they come exactly into position adjacent to the iron tie plates *c* secured on the sleepers *j*.

The creeping of the rail is prevented by the device constituting the invention in the following manner:—

The iron strip *b* attached to the rail foot bears against the iron tie plate *c*, and thereby prevents the rail from moving in the one direction. Since the tie plate is secured to the sleeper by means of the rail spikes or bolts *i*, the pressure set up by the creep of the rail is transmitted to the sleeper *j*. The sleeper is prevented from shifting by the ballast of the permanent way.

The adhesion of the iron strip hammered on to the rail foot may also be increased by making one or two small depressions *k*, with a pointed hammer at the two edges of the rail foot over which the iron strip is bent. The red hot strip is hammered into these depressions and forms, when cold, teeth which engage therein and offer a greatly increased resistance to movements in the longitudinal direction.

The existing devices (resting on the iron tie plate) for preventing rail creep, exhibit the defect that, owing to the heavy lateral pressure, the tie plate bends the rail spikes. This cannot occur with the present invention since, owing to its low cost, the device constituting the invention can be employed on every sleeper or tie plate, with the result that the pressure is distributed among them, in contrast to the existing device, in which the pressure is applied to only 2 or 3 sleepers.

What I claim as my invention and desire to secure by Letters Patent is:—

1. An anti-creeping device for railway rails mounted on tie plates, comprising a plate disposed under the rail and bent over on itself along opposite sides to embrace the rail base, the edges of the base coming inside the last named plate being irregular to permit the surface of the bent over sides to conform to the irregularities during the operation of being bent about said base.

2. The method of anchoring an anti-creeping device to the base flange of a rail, which consists in forming depressions in the opposite sides of the base flange, thereafter placing a plate beneath the base flange with

sides of the plate projecting beyond the sides of the flange and bending the projecting sides of the plate over the notched edges of the flange to cause the material of the plate to enter the notches.

5. The method of anchoring an anti-creeping device to the base flange of a rail, which consists in heating a plate to red heat, thereafter bending the sides of said plate about the base flange, and finally contracting the plate by cooling to increase its gripping power on the rail.

10. 3. The method of anchoring an anti-creeping device to the base flange of a rail, which consists in placing a plate beneath the base flange with the sides projecting beyond the superimposed sides of the said flange and thereafter bending the projecting sides of the plate over the sides 15. of the flange to draw the plate at the bends into the most intimate gripping contact with the rail flange.

15. 4. The herein described method of anchoring an anti-creeping device to the base flange of a rail resting upon a tieplate, which consists in placing a plane plate beneath the base flange with one end abutting the adjacent side of the tieplate, and thereafter bending and contracting the plate about the 20. 25. sides of the flange.

20. 5. An anti-creeping device for railway rails, comprising a plane plate disposed under the base flange of the rail and bent over opposite sides of the rail base to intimately grip the latter, said plate being shrunk subsequent to the bending operation to establish a shrink fit between contacting parts.

25. In testimony whereof I affix my signature
30. ZOLTÁN THOMKA.
